UNITED STATES PATENT OFFICE.

CHARLES E. FRY, OF BLOOMFIELD, IOWA.

SAFETY SIGNAL FOR RAILWAY CROSSINGS.

Application filed March 13, 1923. Serial No. 624,726.

To all whom it may concern:

Be it known that I, CHARLES E. FRY, a citizen of the United States, residing at Bloomfield, in the county of Davis and State 5 of Iowa, have invented certain new and useful Improvements in Safety Signals for Railway Crossings, of which the following is a specification.

My invention relates to improvements in 10 railway crossings and has for the main purpose thereof, the provision of such a device that is comparatively simple of construction, and inexpensive of installation, the same consisting of relatively few parts, and these 15 so correlated in such a manner as to reduce the liability of rearrangement to a minimum.

A further purpose of my invention is the provision of such a railway crossing gate 20 that is positive in its operation and of such a nature as to effectively prevent the passage of vehicles or pedestrians across the track-way.

The nature and advantages of the invention will be better understood when the following detailed description is read in connection with the accompanying drawings, the invention residing in the construction, combination, and arrangement of parts as 30 claimed.

In the drawings forming part of this application, like numerals of reference indicate similar parts throughout Figures 1 to 4 inclusive.

Figure 1 is a side elevational view of my improved railway crossing gate, the same being shown in both full and dotted line positions.

Figure 2 is a top plan view of the railway 40 crossing more clearly showing a form of vertically swinging platform, forming a component part of my invention.

Figure 3 is a detail cross sectional view upon the line 3—3 of Figure 2, this platform 45 being shown in both full and dotted line positions.

Figure 4 is a front or rear elevation, partly in cross section of one of the cable supporting standards that form a part of my 50 invention.

Figure 5 is a side elevational view, partly in cross section of an automatic type of railway crossing signal arm being shown in a raised position.

Figure 6 is a side elevational view of the 55

signal arm supporting standard, the signal arm being shown in an inoperative position, and

Figure 7 is an end elevation of the automatic crossing signal showing more clearly 60 the train control means therefor.

Referring to the drawings in detail, and particularly to Figures 1 to 4 inclusive, A designates the track-way, and B the highway crossing thereover. Between the rails 65 of the trackway A is a filler platform 5, while at one side of the trackway and adjacent one of the rails thereof is a short inclined platform 6, the opposite ends of which carry vertical posts 7. The said roadway A 70 is slightly inclined in a direction towards the said platform 6, as more clearly shown in Figure 3, this roadway terminating at a point a slight distance away from the said platform 6, and carries at its edge, a cross 75 strip 8. Pivoted at 9 to the said platform section 6 is a swinging platform 10, the same adapted for normal alinement between the said platform 6 and cross strip 8.

Adjacent the side of the said roadway is 80 a supporting post 11, the upper end of which carries a pulley 12, and over this pulley is a protecting hood 13. The front edge of said post 11 at a point above the posts 7 carried by the platform 6, has pivotally secured 85 thereto as at 14 a signal arm 15. At a point remote from the said post 11 is an additional post 16, the upper end thereof also carrying a pulley wheel 17 over which is a hood 18. Pivotally secured to the lower end of the 90 post is a control lever 20 and secured at 21 to this lever is an operating cable 22, the same being extended upwardly and engaged over the pulley 17 and thence extending forwardly and extending over the pulley 12 of the 95 post 11. This cable 22 is connected at 23 to the said signal arm 15 and at 24 to the said swinging platform 10.

In view of the above description, it will at once be apparent that when the lever 20 is 100 swung downwardly in the direction of the arrows, Figure 1, the signal arm 15 as well as the platform 10 will be extended to the dotted line positions of Figure 1, the signal arm 15 clearly indicating to pedestrians and the drivers of vehicles the approach of an oncoming train. It will also be clearly noted that when the platform 10 is extended to a vertical position, the same will engage 105 to the posts 7 of the platform 6 for limit- 110

ing the swinging movement of the gate, and when in a vertical raised position, passage across the trackway will be prohibited.

With particular reference to Figures 5, 6 and 7, A' designates the track-way, B' the high-way. At one side of the said highway B' is a post 11', the upper end thereof carrying a pulley 12' over which is a hood 13'. Pivoted to a bracket plate carried by the said post and at a point a considerable distance above the highway B' is a signal arm 15'. At a point remote from the first mentioned post 11' and outwardly of the said track-way A' is another post 16', the front edge of which carries a pair of vertically aligned pulleys 17' enclosed within a hood 18'. Disposed for rocking movement adjacent the lower end of the said post 16' is what may be termed a bell crank 25, the arm 26 thereof extending inwardly and being slightly spaced from the adjacent rail of the track-way for purposes hereinafter described, it being clearly noted that this arm of the said bell crank is curved as clearly shown in Figure 5. Connected to the end of the other arm 27 of said bell crank is a cable 28, the same extending upwardly and engaging over the said pulleys 17'. This cable then extends forwardly and engages over the pulley 12' of the said post 11', it being connected at its opposite end to the signal arm 15'.

Pivoted to the said signal arm 15' at 29 is a rod 30, the lower end of this rod being bent at substantially right angles and formed with a notch 31, it being noted from a consideration of Figure 5, that this rod has sliding movement with a slot 32 in the said post 11', the lower end of this slot being provided with a cross pin 33 for purposes hereinafter described.

In Figures 5 and 7, 34 indicates the usual cow catcher of a locomotive and secured to one side of this cow catcher is an extension arm 35, the same adapted to engage the curved arm 26 of the said bell crank 25 for consequently rocking the same downwardly

for pulling upon the cable 28, which will effectively raise the signal arm 15' to the position shown in Figure 5, it being understood that the said notch 31 at a right angularly bent end of the rod 30 will position over the said cross pin 33 for supporting the said signal arm in its raised operative position.

Pivoted at 36 to a rearwardly extending bracket 37 adjacent the lower end of the said post 11' is a rod 38, one end of the same being bent upwardly and in a position adjacent the rail of the track-way so as to be contacted by the said arm 35 upon the cow catcher 34. The opposite end of this rod extends forwardly and has an inwardly bent portion 39 which has close contact with the said rod 30 when the same is in position as shown in Figure 5, the purpose of this rod being to release the member 30 from the said cross pin 33 when the arm 35 of the cow catcher engages over the bent portion thereof.

Although I have shown and described my improved form of crossing gate and signal arm as being applied to one side of the track-way it is nevertheless to be understood that it is within the purview to install the same at both sides of the track-way without departing from the spirit and scope of the invention, it being also understood that I do not wish to limit myself to the exact structural details as shown.

Having thus described my invention, what I claim as new and desire to secure by Letters-Patent is:—

In railroad crossing signals and gates, an upwardly and transversely swinging platform between the outer side of one of the rails and the road crossing, a post at one side of said platform, a signal arm pivoted to the post, and a single means for simultaneously swinging said signal arm and platform upwardly to an operative position.

In testimony whereof I affix my signature.

CHARLES E. FRY.
